UNITED STATES PATENT OFFICE.

WILLIAM RICHARD HALLETT, OF CASTOR, ALBERTA, CANADA.

HYDROCARBON-ENGINE.

1,106,043.

Specification of Letters Patent.

Patented Aug. 4, 1914.

Application filed June 17, 1913. Serial No. 774,252

To all whom it may concern:

Be it known that I, WILLIAM RICHARD HALLETT, a citizen of the Dominion of Canada, residing at the village of Castor, in the Province of Alberta and Dominion of Canada, have invented certain new and useful Improvements in Hydrocarbon-Engines, of which the following is a specification.

My invention relates to engines more particularly adapted for use in aeroplanes, and my object has been to devise a motor for this and kindred purposes, combining great strength with lightness and free from vibration.

I attain my object by means of the mechanism illustrated in the accompanying drawings, in which—

Figure 1 is a plan view, partly in section, showing the pistons at the limit of their outward stroke. Fig. 2 is a similar view, but showing the pistons at the inward limit of their stroke. Fig. 3 illustrates the valve movement synchronous with the position of the pistons as shown in Fig. 2. Fig. 4 shows the pistons and the rods connecting them, which go to form half of the engine movement. Fig. 5 similarly shows the pistons, rods and cross-head forming the opposite half of the movement. Fig. 6 is a view of one of the end pistons with the piston rods shown sectionally therein. Fig. 7 is a similar view of an intermediate piston.

The engine as illustrated, is of the double acting four cycle type, and I prefer to use a jump spark ignition, but as this forms no part of my present invention I have thought it sufficient to indicate by binding posts the position of the igniting points, leaving it to users of my device to make such connection as they deem advisable for the purpose.

Referring to the drawings which form a part hereof, and in which similar numerals refer to similar parts throughout the different views; 1 is the cylinder of the engine. This is open at both ends, and it is preferably bored to the same diameter throughout its length. The outer surface of the cylinder is grooved circumferentially in order to offer the largest possible radiating surface, this being in accordance with the best engineering practice regarding air cooled motors.

2 and 3 indicate the driving shafts, on the ends of which are shown fragments 4 and 5 of the propellers which would be used were the motor utilized for aerial propulsion.

The shafts 2 and 3 are provided with cranks 6 and 7 which connect, as hereinafter described, with the driving parts of the engine.

In the cylinder 1, and adapted for reciprocating movement therein, are the pistons 8, 9, 10, 11 and 12, and a cross-head 13, the latter being shown in piston shape, though any other shape suitable for guidance by the cylinder would answer equally well.

The evenly numbered pistons 8, 10 and 12 are joined each to each by the rods 14 and 15, being held properly spaced thereon by the jam nuts 16, the whole forming what might be described as a piston unit, and shown separately as Fig. 4. The rods 14 and 15, it will be understood, have sliding passage through the pistons 9 and 11, but are not secured to them in any way. Similarly, the oddly numbered pistons 9 and 11, and the cross-head 13 are joined together by the rod 17 and a similar rod 18, shown only in Fig. 7, the pistons being retained in spaced relation thereon by the jam nuts 19, thus forming the piston unit shown as Fig. 5, the rods 17 and 18 having sliding passage through the pistons 10 and 12, and being unsecured thereto.

It may be further explained that the openings for the rods secured in the pistons 8, 9, 12 and the cross-head 13, are screw-threaded interiorly, the ends of the rods being threaded for engagement with the threads in the openings.

The connecting rod 20 unites the piston 8 with the crank 6, and similarly the connecting rod 21 forms operative union between the cross-head 13 and the crank 7. Thus, if any member of the evenly numbered piston unit receive an impulse it will act upon the crank 2, and an impulse imparted to a member of the oddly numbered unit will be communicated to the crank 3.

On the shaft 2 is a gear 22 adapted for engagement with a gear 23 on the shaft 24 running at right angles to the shaft 2. The shaft 24 passes through the valve chambers 25, 26, 27 and 28, within which are the valves 29, 30, 31 and 32, these being secured to the shaft 24 and adapted to revolve with it.

The valve chambers 25, 26, 27 and 28 connect with the cylinder 1 by the ports 33, 34, 35 and 36 respectively, and with the carbureter 37 by the pipes 38, 39, 40 and 41 which are fed by the main 42 in which is located the throttle valve 43. Also in the valve

chambers are the exhaust ports 44, 45, 46 and 47.

As the construction and operation of the valves form the subject matter of a separate application for a patent which I am making contemporaneously with this, any extended description at the present time would be out of place, I will therefore confine myself to an explanation of the valve movement only in so far as it affects the operation of the engine.

It will be noted in Fig. 3, that the valves are set in sequence, each with a lead of a quarter turn over the next following it, and that the gears 23 and 22 are proportioned in the ratio of two to one, the smaller being upon the crankshaft 2, and that in consequence two revolutions of the crank shaft are required to effect one complete revolution of any one of the valves 29, 30, 31 and 32.

Referring to Figs. 1 and 2 it will be seen that the pistons divided the cylinder 1 into explosion chambers indicated as 48, 49, 50 and 51, each having communication with the valve pertaining to it. On the upper side of the cylinder 1 are shown the binding posts 52, a pair of which are located opposite each of the explosion chambers. The wires 53, forming part of the posts 52, project into the explosion chambers, the points of those of each pair approaching each other in such manner as to allow of an electric discharge passing from one to the other, thus exploding the charge contained in the chamber. As previously mentioned, the current for this purpose may be generated in any manner thought advisable, and the synchronizing of the discharges with the cycles of the engine, be performed in any manner that will produce the required result. By my arrangement of multiple pistons in a single cylinder it becomes possible to secure simultaneously at every movement of the pistons, the four necessary operations of a successful hydrocarbon motor, viz—the explosion in one chamber, the compression of a charge of explosive fluid in a second chamber, the taking of a fresh charge in a third chamber, and the exhaustion of waste gases from the fourth chamber. I am not aware that this has previously been done. To illustrate these operations attention is called to the position of the pistons as shown in Fig. 2. In this figure an explosion has just taken place in the chamber 48 giving a half revolution to the cranks 6 and 7, throwing the pistons 8 and 9 apart and operating through them, the other parts of the piston units to which they belong. Thus, the pistons 11 and 12 were brought together, compressing between them, the charge of explosive mixture in the chamber 51, and placing that chamber in readiness as the next to be exploded. The pistons 10 and 11 were

thrown apart, operating to draw a fresh charge of fluid from the carbureter into the chamber 50, and the pistons 9 and 10 were brought together exhausting the waste gases left in the chamber 49 from the previous explosion.

That the operations in the different chambers has been as described is shown by the positions of the valves in Fig. 3. In this figure the valve 29, which pertains to the chamber 48, is shown as just moving to "exhaust" position, the valve 32 just reaching the "ready to explode" position, the valve 31 "ready to compress," and the valve 30 "ready to charge." These operations are continuous and the next explosion, due to take place in the chamber 51, will serve to place the pistons in the position shown in Fig. 1, and bring about another half revolution of the cranks 6 and 7.

As the valves advance a quarter turn for each operation it will be seen that it requires two revolutions of the crank shafts to produce the four operations—explosion, exhaust, recharge and compression—required in each chamber.

As the piston units in the cylinder have no connection with each other, the engine works with equal freedom in both directions, thus there is double action and freedom from vibration.

It is of course quite feasible to connect the shafts 2 and 3 in a positive manner, so that they would be compelled to work together, and to add a flywheel, and for certain purposes this might be advisable, but when the engine is used as originally intended it is preferable that each end be independent of the other.

From the foregoing description it will be seen that I have designed a motor, direct in action, and combining few parts with great simplicity of operation, and that the power developed depends only upon the size to which the motor may be built, and the strength of the material used.

Having thus fully described my said invention what I claim is—

1. A hydro-carbon engine comprising a cylinder having a plurality of pistons reciprocable therein, certain of said pistons relatively immovably connected to form a piston unit and the other of said pistons relatively removably connected to form another piston unit, cranks at the ends of said cylinder and rods connecting said piston units with said cranks, the spaces between the members of the one piston unit and those of the other forming chambers for the operations required in an engine of the character described and the members of said piston units being sufficiently numerous to provide between them chambers for all of said operations simultaneously, said operations causing the reciprocations of said piston units

in opposite directions and the rotation of said cranks.

2. A hydro-carbon engine comprising a cylinder having a plurality of pistons reciprocable therein, rods connecting the alternate pistons into separate groups, those of each group being relatively immovable and the rods connecting the related members of one group passing through the intervening members of the other group, a crank at each end of the cylinder and rods connecting each of said groups with one of said cranks, the spaces between the members of one of said groups and those of the other forming four chambers adapted for the simultaneous reception in one chamber of a charge of explosive mixture, the compression in a second chamber of a charge of explosive mixture, the explosion of a charge in a third chamber and the exhaustion of waste gases from the fourth chamber, said operations being constantly repeated, said groups of pistons being thereby oppositely reciprocated and said cranks rotated.

3. A four cycle hydro-carbon engine comprising a cylinder, five pistons and a cross-head in the cylinder, rods connecting the center and two outer pistons to form a three member piston unit and rods connecting the remaining pistons to form a two member piston unit, the rods connecting said three

member unit passing through the members of said two member unit and the rods connecting said two member unit passing through the central member of said three member unit and one of the outer members thereof and connecting with the cross head, a crank-shaft at the end of said cylinder and a rod connecting said cross head with said crank-shaft, the piston of said three member unit adjacent the opposite end of the cylinder connecting with a similar shaft in a similar manner, the throw of the cranks on said shafts defining the movement of said piston units to and from each other in said cylinder, the opposing faces of the members of one unit and those of the other forming four chambers each adapted for the four operations, the reception of a charge of explosive mixture, the compression of the charge, the explosion of the charge and the exhaust of the waste gases, said operations following each other in regular rotation in each chamber and producing a half revolution of said shafts at each explosion.

In testimony whereof I have affixed my signature in presence of two witnesses.
